(57) **CLAIM**

The ornamental design for an electric cooking apparatus, as shown and described.

DESCRIPTION

FIG. 1 is a top right perspective view of an electric cooking apparatus according to the present invention.

FIG. 2 is a top view of the electric cooking apparatus of FIG. 1.

FIG. 3 is a front view of the electric cooking apparatus of FIG. 1.

FIG. 4 is a bottom view of the electric cooking apparatus of FIG. 1.

FIG. 5 is a rear view of the electric cooking apparatus of FIG. 1.

FIG. 6 is a cross-sectional view taken along line 6—6 of the electric cooking apparatus of FIG. 2; and,

FIG. 7 is a left side view of the electric cooking apparatus of FIG. 1.

The double-dot dashed lines in FIG. 1 illustrate an electrical control device, and form no part of the claimed design. The double-dot dashed lines in FIG. 3 illustrate an electrical control device and feet, and form no part of the claimed design. The double-dot dashed lines in FIG. 4 illustrate feet and ventilation openings, and form no part of the claimed design. The double-dot dashed lines in FIG. 5 illustrate feet, and form no part of the claimed design. The cross-sectional view presented in FIG. 6 illustrates the contour and configuration of the exterior surfaces, which are not apparent from the other exterior views, at cut line 6—6. The double-dot dashed lines in FIG. 6 delineate the boundary of the claimed design. The double-dot dashed lines in FIG. 7 illustrate feet, and form no part of the claimed design. The right side of the electrical cooking apparatus according to the present invention is a mirror image of the left side of the electrical cooking apparatus as illustrated in FIG. 7, for example, and is omitted.
